UNITED STATES PATENT OFFICE.

WILLIAM P. TAGGART, OF PHOENIXVILLE, PENNSYLVANIA.

CAR-COUPING.

SPECIFICATION forming part of Letters Patent No. 269,485, dated December 19, 1882.

Application filed September 22, 1882. (No model.)

To all whom it may concern:

Be it known that I, WILLIAM P. TAGGART, a citizen of the United States, and a resident of Phoenixville, Chester county, Pennsylvania, 5 have invented certain Improvements in Car-Couplings, of which the following is a specification.

The main object of my invention is to so construct a coupling for railroad-cars that the 10 operations of coupling and uncoupling can be readily effected without the necessity of the brakeman going between the cars, the coupling being secure, but permitting perfect freedom of movement of the cars in turning curves, 15 and being adapted for the coupling of cars of different heights.

A further object of the invention is to adapt the coupling for use upon cars having no bumpers.

20 In the accompanying drawings, Figure 1, Sheet 1, is a side view of my improved car-coupling before the coupling is effected; Fig. 2, a longitudinal section of the same after coupling; Fig. 3, a perspective view of the 25 coupling-hook; Fig. 4, Sheet 2, a sectional view, showing the parts in the act of coupling; Fig. 5, an end view of the draw-head and coupling-hook, and Fig. 6 a plan view of Fig. 3.

A represents one of the draw-heads of a car, 30 and B the draw-head of another car, which is to be coupled to that having the draw-head A. To said draw-head A a hook, D, is pivoted by means of a transverse pin, a, the latter being adapted to slots b in the sides of the draw-head, 35 and said slots being open at the top, so that the hook can be readily inserted into or removed from the draw-head when held in such a position that a projection, d, on the hook will clear a transverse pin, e, in the head, said 40 projection and pin preventing the accidental displacement of the hook when the cars are coupled. A plate, f, is pivoted to the hook D, and is adapted to close the mouth or opening of said hook, a link, g, on the plate being connected to a chain, h, which extends to any convenient point, so that it may be reached by the brakeman without the necessity of going between the cars.

To the draw-head B a link, F, is pivoted by 50 means of a transverse pin, a, adapted to open-ended slots b in the head, the means of hang-

ing the link being similar to those employed for the hook, and said link being likewise prevented from being accidentally displaced by means of a projection, d, and transverse pin e. 55

Pivoted to each of the draw-heads is a yoke, G, and on each yoke is formed a segmental rack, m, which engages with a pinion, n, on a shaft passing through the draw-head, said shaft being furnished with a crank, so that it 60 may be readily turned to effect the raising and lowering of the yoke, the latter being retained in any position to which it has been adjusted, owing to the engagement of a spring-pawl, p, with the teeth of the pinion n. These yokes 65 are only intended to be used on cars which are not supplied with bumpers, the yoke of one head, A, being elevated, so as to serve as a bumper, and the yoke of the other head, B, being depressed, so as to be out of the way, 70 as shown in Figs. 1, 2, and 4.

The operation of coupling is as follows: The hook D is first elevated, as shown in Fig. 1, the chain h being allowed to hang slack, and the hook being supported by the pin e, so as 75 to have a slight incline rearwardly from the pivot-pin and be thus self-retaining in the position shown. As the cars approach each other the link F enters one of a series of openings, x, in the yoke G, and said yoke comes into contact with the end of the draw-head B. The jar due to this contact causes the hook D to fall forward and engage with the link F, as shown in Fig. 4. When the cars are drawn apart the plate f falls and closes the opening 85 of the hook, as shown in Fig. 2, so as to effectually prevent the accidental uncoupling of the cars. Uncoupling is effected by an upward pull upon the chain h, the first effect of which is to lift the plate f and then to elevate the 90 hook. When the hook is fully elevated and the chain h released the link g is prevented from falling too far by stops y on the hook, as shown in Fig. 1.

The object of providing the yokes G with a 95 series of perforations x is to permit the coupling together of cars of different heights; but it will be evident that a single opening of large size in the yoke would answer the same purpose. Such a large opening, however, would detract somewhat from the strength of the yoke. Either the hook end or the link end of

my improved coupling can be coupled to an ordinary link-and-pin draw-head, and the improved coupling permits ample movement of the cars in respect to each other in turning curves.

The object of providing the draw-head B, as well as the head A, with a yoke G is to permit the coupling of said head B to a car having a projecting hook, the yoke of the head B in this case acting as a bumper, and the link being caused to drop onto the hook in the same manner as the hook D drops into the link.

In some cases the draw-heads A and B may be permitted to slide longitudinally, in which case the fall of the hook or link may be caused by direct contact with the end of the car as the head slides inward, instead of being due solely to the jar caused when the cars come together.

I claim as my invention—

1. The combination of a draw-head with a hook or link pivoted thereto by means of a

transverse pin, a, adapted to open-ended slots b in the head, as set forth. 25

2. The combination of the draw-head having open-ended slots b and a transverse pin, e, with the hook or link having a pivot-pin, a, and projection d, as set forth.

3. The combination of the draw-head A with the hook D, pivoted thereto, and having a closing plate, f, and means for lifting the same, as set forth. 30

4. The combination of a draw-head with a yoke, G, adapted to serve as a bumper, as 35 specified.

5. The combination of a draw-head with a yoke, G, adapted to serve as a bumper, and having a series of openings, x, as set forth.

In testimony whereof I have signed my name 40 to this specification in the presence of two subscribing witnesses.

WILLIAM P. TAGGART.
